PENCIL SHARPENER

Maurice Charles Garrett, New York, N. Y.

Application March 13, 1947, Serial No. 734,367

7 Claims. (Cl. 120—96)

1

This invention is an improvement in pencil sharpeners, and particularly a pencil sharpener of the mechanical type comprising a casing with movable cutters therein and connections operable from the outside of the casing for actuating said cutters.

An important object of the invention is to provide a pencil sharpener of small sizes, easy to use and adapted to be conveniently and handily carried about in a pocket or handbag or otherwise upon the person of the owner.

A further object is to provide a pencil sharpener of small compass and suitable shape, so as to be portable, which can be worked efficiently, and is simple in construction, and inexpensive to produce.

The nature and advantages of the invention are made clear in the following description, and the novel features are defined in the appended claims. This disclosure however, is explanatory only and I do not wish to be restricted to the exact design specified herein, but reserve the right to make alterations in details without departure from the principle of the invention or omission of any of the essential characteristics thereof.

On the drawings:

Figure 1 is an end elevation, showing the operating connections of the sharpener in one position, ready for the working stroke.

Figure 2 is a similar view with the operating connections at the end of the working stroke.

Figure 3 is a longitudinal section through the sharpener.

Figure 3a is a detail thereof.

Figure 4 is a perspective view of the cutter.

Figure 5 is a cross section on line 5—5 of Figure 3; and

Figure 6 is a detail showing a modification.

The sharpener comprises a casing 1, cylindrical in shape, with one end closed, as shown at 2; the opposite end being open. The casing encloses a cutter member 3, and the opposite end of the casing has a disk 4, with a central aperture 5, secured therein. This aperture is in line with a tapering space enclosed by bars 6, which make up the principal part of the body of the cutter; and the pencil (indicated at P) to be sharpened is inserted through the aperture 5 into the space enveloped by the bars 6. One extremity of the cutter has a projection or short shaft 7 affixed thereto, and extending through an opening in the end 2 to the outside of the casing. Affixed to this projection 7 on the outer face of the end 2 by any suitable means is a pinion 8, and piv-

2

otally mounted on the casing is a rocker or lever 9, which actuates a rack member 10 arranged to mesh with the pinion 8. When the sharpener is held in the hand, pressure on the rocker pushes the rack down and turns the pinion and the cutter 3. The member 10 has the form of a frame with an opening or slot 11 which receives the pinion 8, and has internal teeth 12 on one side to mesh with the pinion 8.

The cutter member is made up of rounded ends comprising a circular plate or disk 13 adjacent the end 2 and a circular ring 14 at the opposite end. This ring rotatably engages another ring 15, with a shoulder that forms a bearing for the ring 14, the ring 15 being affixed within the casing 1, just back of the disk 4; so that the ring 14 is covered by the disk 4. The disk 13 and the ring 14 are rigidly united by the longitudinal bars 6, of any suitable shape, with their faces adjacent the axis of the cutter concave and conical, as illustrated at 16. The bars 6 are separated along their adjacent edges; and one outer face of each is finished to present shouldered seats for cutter blades or elements 17. The bars thus define a space of the configuration required for the end of a pencil, and the blades all have their cutting edges in the right converging positions. To hold the blades 17 fast on the bars 16, screws or the like 18 are utilized, and the bars can be made rigid with the parts 13 and 14 in any suitable manner. The disk 13 fits the bore of the casing 1 and can revolve therein.

The rocker 9 is attached at one end to the outside of the casing adjacent the disk 4 by means of bearing lugs 19 on the casing and trunnions 20 on the rocker. It is transversely curved to suit the contour of the casing. The rack is attached to the opposite end of the rocker lever by means of pivot pins 21, engaging slots 22 in lugs or bearings 23 on the underside of the rocker. The connections, comprising the rack and pinion include means for causing the cutter to rotate in one direction only, and to this end the cutter makes its working stroke when the rack moves in the direction of the arrow in Figure 1; but the rack is unmeshed from the pinion 8 when it moves in the opposite direction. The rocker has a projection 24 at one side on the adjacent end, this projection being bent down at the side thereof, and clearing the end 2 of the casing. Uniting this projection to the rack are two links 25, pinned to said parts at their opposite ends. These links tend to assume the diagonal positions presented in Figure 2 because of a tension spring 26 affixed to the projection 24 at

one end and to the rack 10 at the other. In Figure 1, the links hold the rack 10 against the pinion 8; and in Figure 2, the spring 26 maintains the pinion and the rack out of engagement.

The rack moves in a guide 27, a little wider than the rack on the end 2 over the pinion 8. This guide has shoulders 28, and is affixed to the end 2 of the casing at its outturned ends 29. A leaf spring 30 affixed to the casing tends to lift the rocker and rack, and a similar spring 31 attached to the casing has its end entering an aperture 32 in the rack and resists motion from the position of Figures 1 and 3.

When a pencil is thrust into the sharpener, the rocker 9 is pressed down by hand to cause the rack 10 to rotate gear 8 and cutter 3. So long as the rocker is held away from the casing 1 by the spring 30, the spring 26 tilts the rack about the end of the spring 31 as a pivot to the extent permitted by the slots 22 of the lugs 23, which receive the ends of the pins 21. The rack 10 is thus unmeshed from the pinion 8 and the spring 31 holds the rack 10 motionless till the rocker has moved far enough to cause the links 25 to take positions shown in Figure 1, stretching the spring 26 and moving the rack to engage the pinion 8. Further pressing of the lever 9 now rotates the pinion 8 and cutter 3. The end of the spring 31 is smaller than the hole 32.

When the pressure on the rocker is eased the spring 30 lifts the rocker, but the rack does not immediately follow because of the friction of the pencil in the cutter. The first reverse motion of the rocker as indicated in Figure 2, therefore, swings the links 25 to diagonal position and the spring 26 pulls the rack 10 out of mesh with the pinion 8. Both springs 30 and 31 now cooperate to return the rocker 9 and rack 10 to starting positions. Thus the cutter always rotates in one direction and never backward.

On the ends of the casing are outside grooved ribs 33 to receive the ends of a sliding closure 34. This closure overlies an opening 35, through which the casing can be emptied of dust and shavings when the closure 34 is moved to clear the opening 35.

Figure 6 shows the pinion 8 connected to the projection or shaft 7 by forming these two parts so as to constitute a one-way acting ball-clutch connection. The pinion has tapering recesses 36 in the edge of the opening therethrough; and in these openings are balls or rollers 37. The recesses 36 are so arranged that when the rack moves down with reference to Figure 6, the pinion is revolved; and when the rack makes its return stroke, the pinion revolves freely and does not turn the cutter. The links 25 and springs 26 and 31 are discarded and the guide 27 fits over the rack more closely.

In both forms of the invention the slots 22 are wide enough as shown in Figure 3a for the pins 23, to give good operation when the rocker is pressed down.

Having described my invention, what I believe to be new is:

1. A sharpener comprising a casing, a cutter member therein and having a projection, the casing having an opening through which said projection extends to the outside thereof, a rocker

pivotedly mounted on the casing, and connections between the rocker and said projection to actuate the cutter member.

5 2. The sharpener according to claim 1, wherein said rocker has the form of a lever pivotally attached to the casing and said connections comprise gear teeth on said projection and a rack for meshing therewith and united to said lever.

10 3. The sharpener according to claim 1, wherein said rocker has the form of a lever pivotally attached to the casing and said connections comprise gear teeth on the projection, a rack for engaging said teeth and united to the lever, and parts attached to the lever and the rack and operable to control the latter to impart motion in only one direction to the cutter member.

15 4. The sharpener according to claim 1, wherein a leaf spring is disposed between the casing and the rocker to return the latter to starting position.

20 5. A sharpener comprising a casing, a cutter member therein, said member having rounded ends, bars joining said ends, blades secured along the length of said bars and having their edges converging about a central space in the cutter, 25 the casing having an opening in registry therewith, a shouldered ring in the casing having a seat for one of said ends, the opposite end having a projection extending to the outside of the casing, and means on the projection and outside of the casing to operate the cutter, said means comprising a rocker pivotally mounted on the casing.

30 6. A sharpener comprising a casing, a cutter in the casing having a projection, the casing having an opening through which the projection extends, a pinion fixed to the projection on the outside of the casing, a rocker pivotally mounted on the casing, a rack attached to the rocker for meshing with said pinion, a guide for said rack on the end of the casing and covering said pinion, 40 the lever having a turned-down projection adjacent the rack, a pair of pivoted links joining the rack to the projection, a coiled tension spring between said rack and said projection, the rocker having slotted bearings, and the rack having pivot pins engaging said bearings and springs on the outside of the casing, separately engaging the rack and the rocker, for the purpose set forth.

45 7. The sharpener according to claim 1 wherein said connections embrace a pinion having a one-way clutch connection with the projection to be rotatable by the rack in one direction only.
